UNITED STATES PATENT OFFICE.

MARIE E. TUTTLE, OF BUTTE, MONTANA.

MATCH-SAFE.

1,017,708.

Specification of Letters Patent.

Patented Feb. 20, 1912.

Application filed July 10, 1911. Serial No. 637,820.

To all whom it may concern:

Be it known that I, MARIE E. TUTTLE, a citizen of the United States of America, residing at Butte, in the county of Silverbow 5 and State of Montana, have invented certain new and useful Improvements in Match-Safes, of which the following is a specification.

This invention relates to match safes, the 10 object of the invention being to provide an improved device of this character, constructed in such manner as to maintain matches in a position convenient of access, and one that may be readily suspended upon 15 a wall or other support.

A further object of the invention is the provision of a match safe of the character above described, provided with a burned match receiving compartment and holder 20 which may be readily withdrawn when desired, for the purpose of emptying the same without disturbing the usable matches still contained within the match safe.

A further object of the invention is the 25 provision of a match safe provided with striking portions upon all of its surfaces.

Further objects and advantages of the invention will be set forth in the detailed description which now follows:

30 In the accompanying drawing, Figure 1 is a front elevation of a match safe constructed in accordance with the invention, Fig. 2 is a side elevation thereof, and Fig. 3 is a vertical section.

35 Like numerals designate corresponding parts in all of the figures of the drawing.

Referring to the drawing, the numeral 5 designates a wall or other support and 6, a nail upon which the improved match safe is 40 supported. This nail passes through an opening 7 formed in the upstanding portion 8 of the wall of the casing 9. A vertically sliding door 10 normally closes an opening 11 in the rear portion of this casing and 45 provides means for the insertion into the rear compartment 12 of said match safe, of boxes of matches indicated at 13. The compartment 12 is in communication with a forwardly extending bottom compartment 14

50 which has an inclined bottom 15 and is normally closed by a hinged cover 16. This cover is secured to the front wall 17 of the casing 5 by spring hinges 18, whereby it is normally held in closed position. The upper face of the cover 16 is covered by a sand paper or other abrasive sheet 19 and the

front, side and top walls of the casing 5 (it being understood that the casing is of tin or like metal) are stamped out to form raised portions 20, which may be, if desired, of heart shape, and the faces of these raised portions are sanded or otherwise rendered abrasive to adapt them for the striking of matches thereupon.

A transverse opening 21 is in communication with a compartment 22 that is separated from compartments 13 and 14 by walls 23 and 24, and this compartment serves to receive a burned match receptacle 25. The receptacle 25 is provided with a knob or handle 26.

The front wall 17 of the casing is provided with a burned match receiving opening 27, the metal at the inner edge of which is bent inwardly at 28 to overlie the receptacle 25. This insures that the burned matches will fall within said receptacle and that they will not fall down between said receptacle and the front wall, and by lodging therein, prevent the ready withdrawal of the receptacle 25.

It will be apparent by an inspection of Fig. 3, that the sliding door 10 projects a sufficient distance above the wall 8 to permit of its being readily grasped when it is desired to open said door and yet the fact that the nail 6 projects through openings formed both in said door and in the wall 8, provides for the ready hanging up of the match safe when desired.

It will be apparent from an inspection of Fig. 3 that if a box or boxes of matches be placed in position in the compartment 12, with the usual slidable cover of the box moved to partially uncover the tray of the box, it is apparent that the matches will roll down the inclined bottom 15 to a position where they may be reached when the lid 16 is lifted.

By providing the abrasive sheet 19 and the roughened or abrasive raised surfaces 20, it will readily be understood that numerous striking surfaces are presented.

From the foregoing description it will be seen that simple and efficient means are herein provided for accomplishing the objects of the invention, but while the elements shown and described are well adapted to serve the purposes for which they are intended, it is to be understood that the invention is not limited to the precise construction set forth, but includes within its purview

such changes as may be made within the scope of the appended claims.

Having described my invention, what I claim is:

- 5 1. A match safe comprising a main body portion and a forwardly extending portion at the bottom thereof having an open top, a cover hinged to the front wall of the main body portion and covering the said extension, a cover hinged to the front wall of the main body portion and covering the said extension, 25
- 10 said main body portion being divided into two parts, the rearmost of which communicates with the interior of said forwardly extending portion, and a drawer-like receptacle slideable through one of the side walls of said main body portion, the rear of the main body portion being open, 30 a vertically sliding door for closing the rear side of the main body portion and an upward extension upon the main body portion, there being registering openings formed through the upward extension and the sliding door as and for the purposes set forth.
- 15 of said main body portion, there being an opening formed through said front wall and a deflector plate arranged inside said opening and overhanging said receptacle. 35
- 20 2. A match safe comprising a main body portion and a forwardly extending portion at the bottom thereof having an open top,

a cover hinged to the front wall of the main body portion and covering the said extension, said main body portion being divided into two parts, the rearmost of which communicates with the interior of said forwardly extending portion, and a drawer-like receptacle slideable through one of the side walls of said main body portion, the rear of the main body portion being open, 30 a vertically sliding door for closing the rear side of the main body portion and an upward extension upon the main body portion, there being registering openings formed through the upward extension and the sliding door as and for the purposes set forth.

In testimony whereof, I affix my signature in the presence of two witnesses.

MARIE E. TUTTLE.
